ATTORNEY

UNITED STATES PATENT OFFICE.

GEORGE N. CLAPP, OF SEVEN MILE, ASSIGNOR OF ONE-HALF TO PLEASANT R. SHEPHERD, OF HAMILTON, OHIO.

APRON-GEARING.

SPECIFICATION forming part of Letters Patent No. 295,906, dated April 1, 1884.

Application filed June 13, 1883. (No model.)

To all whom it may concern:

Be it known that I, GEORGE N. CLAPP, of Seven Mile, Butler county, Ohio, have invented certain new and useful Improvements in 5 Apron-Gearings, of which the following is a specification.

This invention relates to gearing for endless carrier-belts—such, for instance, as are used on self-binding harvesters.

10 The invention relates, particularly, to the construction of the toothed portions of driving-roller and apron, whereby the mere friction of smooth aprons is supplanted by toothed gearing of an elastic nature and of peculiarly simple construction.

15 The invention will be understood from the description and drawings.

In the accompanying drawings, Figure 1 represents a portion of an apron embodying my 20 invention, shown in face elevation with a part broken away to exhibit the inner surface of the apron; and Fig. 2 represents an edge view of the same, some parts being in section.

25 In the drawings, A represents part of an endless canvas apron; B, the roller which drives the apron; C, the roller-shaft or journals; D, the roll-pulley by which the roll receives its motion; E, a shell-pinion made in halves and secured to the roll; F, the teeth of 30 the pinion; G, a leather strap, secured to the inner surface of the apron in line with the pinion; H, a series of teeth formed in pairs and secured to the strap; I, the individual teeth of the series; J, the ears by which each pair of 35 teeth is secured to the strap, and K the space between the two teeth of a pair.

The series of teeth H are formed of small rectangular frames of metal.

40 The sides of the frame form teeth properly spaced to suit the pinion, and each frame is so

located with reference to its neighbor as to maintain the proper tooth spacing throughout the series.

In practice the teeth are first secured to the straps and then the straps to the apron. There 45 may be as many of the straps and pinions as the width of the apron renders advisable.

The pinion being in halves, as described, permits the ready application of this system of 50 gearing to old machines.

The straps re-enforce the apron at the strain-points and relieve the apron from all the strain of driving.

Aprons provided with interior cleats in combination with a longitudinally-grooved driving-roll have been devised by others. I disclaim such as of my invention. 55

It is not new to drive an endless chain by means of a sprocket-wheel, and an endless apron has been arranged over such chains and 60 attached to the chain at one point, so as to be drawn along by this single attachment. I disclaim such as of my invention.

I claim as my invention—

1. The apron-carrying roll provided with 65 short teeth, the canvas apron, and the metallic teeth formed in independent pairs and secured to the interior of the apron, all combined substantially as specified.

2. The combination of the apron-carrying 70 roll provided with short teeth, the apron, the re-enforcing draft-straps, and the metallic teeth arranged in sections and secured independently to the strap, substantially as and for the purpose set forth.

GEORGE N. CLAPP.
